**1-THIOCARBAMYL-2-IMIDAZOLIDINETHIONES
AND A PROCESS FOR THEIR PREPARATION**

Wolfgang Gündel, Dusseldorf-Oberkassel, Germany, assignor to Dehydag, Deutsche Hydrierwerke G.m.b.H., Dusseldorf, Germany, a corporation of Germany
No Drawing. Filed Apr. 19, 1961, Ser. No. 103,962
Claims priority, application Germany, Apr. 30, 1960,
D. 33,234.

10 Claims. (Cl. 260—247.1)

This invention relates to a process for producing 1-thiocarbamyl-2-imidazolidinethione and N-substituted derivatives. These compounds are also known as N-thiocarbamyl substituted ethylene thioureas.

In United States patent application Serial No. 91,331, filed February 24, 1961, there is described a process of producing substituted thioureas. According to this process, an aliphatic ester of an N-mono-substituted dithiocarbamic acid, which ester contains a free hydrogen atom attached to the nitrogen atom in the acid moiety and a water-solubilizing group in the alcohol moiety, is dissolved in water and reacted at a temperature between about 20° C. and about 100° C. with the stoichiometric amount of a reactant selected from the group consisting of ammonia, primary monoamines, secondary monoamines and polyamines in the presence of an alkaline reactant selected from the group consisting of alkali metal hydroxides, ammonia, primary monoamines, secondary monoamines and polyamines.

In this manner it is possible to obtain mono-, di- or tri-substituted thioureas of the general formula:

wherein R is (a) an aliphatic hydrocarbon radical which may be unsubstituted or substituted or interrupted by hetero atoms or hetero atom groups or (b) an aromatic radical, and R₁ and R₂ are hydrogen or hydrocarbon radicals which may be unsubstituted or substituted or also interrupted by hetero atoms or hetero atom groups; these radicals may be identical to or different from each other. R can also represent an alkylene group containing at least three methylene groups, in which case the above formula can be written:

Specifically, the process results in substituted thioureas of the formula:

wherein z is an integer selected from 1 and 2; R is a radical selected from the group consisting of (A) alkylene having from 3 to 18 carbon atoms and the formula:

wherein R₃ represents a member of the group consisting of hydrogen and lower alkyl and w represents an integer selected from 1 to 8, when z is 2 and (B) alkyl having from 1 to 22 carbon atoms, alkenyl having from 3 to 22 carbon atoms, phenylalkyl having from 7 to 22 carbon atoms, phenyl, naphthyl, alkylphenyl having from 7 to 22 carbon atoms, alkynaphthyl having from 11 to 22 carbon atoms, nitrophenyl and nitroaminophenyl, when z is 1; and R₁ and R₂ represent radicals selected from the

2

group consisting of hydrogen, alkyl having from 1 to 22 carbon atoms, alkenyl having from 3 to 22 carbon atoms, hydroxylalkyl having from 2 to 22 carbon atoms, cycloalkyl having from 5 to 6 carbon atoms, alkylcycloalkyl having from 7 to 22 carbon atoms, alkylcycloalkenyl having from 7 to 22 carbon atoms, aminoalkyl having from 2 to 22 carbon atoms, phenyl, naphthyl, aminophenyl, aminonaphthyl, phenylalkyl having from 7 to 22 carbon atoms, alkylphenyl having from 7 to 22 carbon atoms, alkynaphthyl having from 11 to 22 carbon atoms, alkylaminoalkyl having from 3 to 22 carbon atoms, dialkylaminoalkyl having from 4 to 22 carbon atoms, aminoalkylaminoalkyl having from 4 to 22 carbon atoms, and, when taken together, alkylene having 4 to 5 carbon atoms, alkylaminoalkyl having 4 carbon atoms and alkyloxyalkyl having 4 carbon atoms.

It is believed that in this process, under the influence of alkali, which in many cases may be replaced by an additional molecule of amine, an isothiocyanic acid ester (mustard oil) is initially formed in accordance with the following equation:

This isothiocyanic acid ester then reacts by addition with the ammonia or the primary or secondary amine in known fashion, and leads to the formation of the mono-, di- or tri-substituted thioureas in accordance with the following equations:

By analogous procedures, it is also possible by this process to obtain alkylene-bis-thioureas wherein both valences of the terminal nitrogen atoms are occupied by organic radicals. Alkylene-bis-thioureas which may be obtained by the method described below have the general formula:

wherein R represents an alkylene group having from 3 to 18 carbon atoms and the formula:

wherein R₃ is a member selected from the group consisting of hydrogen and lower alkyl and w represents an integer selected from 1 to 8.

These products are obtained by reacting an aliphatic diester of alkylene-N,N'-bis-dithiocarbamic acid, which diester contains free or replaceable nitrogen atoms in the acid moiety and a water-solubilizing group in each alcohol moiety, and whose alkylene group has from 3 to 18 carbon atoms and the formula:

wherein R₃ is a member selected from the group consisting of hydrogen and lower alkyl and w represents an integer selected from 1 to 8, with two mols of ammonia

or two mols of a primary or secondary amine in the presence of an alkali.

I have now found that 1-thiocarbamyl-2-imidazolidinethione and N-substituted derivatives may be obtained by reacting an aqueous solution of an aliphatic ester of ethylene-1,2-bis-dithiocarbamic acid, which ester contains a free hydrogen atom attached to the nitrogen atom in the acid moiety and a water-solubilizing group in the alcohol moiety, with ammonia or primary or secondary monoamine or polyamine in the presence of alkalis, preferably alkali metal hydroxides. If desired, it is possible to operate without the addition of alkali metal hydroxides, if a corresponding increase in the amount of ammonia or amine is provided.

It is an object of the invention to produce ethylene thiourea derivatives substituted on one of the nitrogen atoms by a thiocarbamyl or N-substituted thiocarbamyl radical by reactions conducted in aqueous media.

It is a further object of this invention to produce 1-thiocarbamyl-2-imidazolidinethione and derivatives substituted on the nitrogen atoms by reacting ammonia or an amine with an aqueous solution of an aliphatic ester of ethylene-1,2-bis-dithiocarbamic acid, which ester contains a free hydrogen atom attached to the nitrogen atom in the acid moiety and a water-solubilizing group in the alcohol moiety in the presence of an alkali.

These and other objects of the invention will become apparent as the description thereof proceeds.

When aliphatic esters of ethylene-1,2-bis-dithiocarbamic acid or corresponding bis-dithioesters which have hydrocarbon substituents attached to the ethylene radical, that is, for example with a bis-dithioester of the general formula:

wherein R represents hydrogen or a lower alkyl group and X represents the alcohol moiety containing a water-solubilizing group, are reacted with ammonia or an amine in the presence of an alkali, contrary to expectations, the 40 intermediate bis-isothiocyanic acid esters of ethylene of the formula:

which form under the influence of the alkali, do not combine with two molecules of the primary or secondary amine, but rather with only one molecule, even if an excess of the amine is present. The compounds formed in this manner do not react in the cold with amines and thus no longer contain a free isothiocyanate group. This is indicated with certainty by their infrared spectra, so that it is justified on the basis of their composition and their behavior to designate them as derivatives of dithiobiurets in accordance with the following tautomeric formulas:

or

wherein R is a radical selected from the group consisting of hydrogen and lower alkyl; and R₁ and R₂ represent

radicals selected from the group consisting of hydrogen, alkyl having from 1 to 22 carbon atoms, alkenyl having from 3 to 22 carbon atoms, hydroxyalkyl having from 2 to 22 carbon atoms, cycloalkyl having from 5 to 6 carbon atoms, carboxyalkyl having from 2 to 8 carbon atoms, alkylcycloalkyl having from 7 to 22 carbon atoms, alkylcycloalkenyl having from 7 to 22 carbon atoms, aminoalkyl having from 2 to 22 carbon atoms, phenyl, naphthyl, aminophenyl, aminonaphthyl, phenylalkyl having from 7 to 22 carbon atoms, alkylphenyl having from 7 to 22 carbon atoms, alkylnaphthyl having from 11 to 22 carbon atoms, alkylaminoalkyl having from 3 to 22 carbon atoms, dialkylaminoalkyl having from 4 to 22 carbon atoms, aminoalkylaminoalkyl having from 4 to 22 carbon atoms, and when taken together, alkylene having 4 to 5 carbon atoms, alkylaminoalkyl having 4 carbon atoms and alkyloxyalkyl having 4 carbon atoms.

The above formulas designating the compounds as 1-thiocarbamyl-2-imidazolidinethiones are specially indicated by the fact that secondary amines, such as diethylamine, where another formulation (7-membered ring) is not possible, react in the same manner.

The practical performance of the reaction is effected by first reacting, in accordance with known methods, 1,2-ethylene diamine or also 1,2-ethylene diamines whose hydrogen atoms are replaced by preferably short chain hydrocarbon radicals of the formula:

wherein R represents a member selected from the group consisting of hydrogen and lower alkyl, such as 1,2-propylene diamine, 2,3-butylene diamine and the like, in aqueous solution with two equivalents of carbon disulfide and alkali metal hydroxide, preferably in the cold, and subsequently reacting the ethylene-1,2-bis-dithiocarbamic acid salt formed thereby with two equivalents of an alkali metal salt of as reactive as possible lower haloalkanoic acid (such as chloroacetic acid and chloropropionic acid) or with a lower haloalkane sulfonic acid (such as bromoethane sulfonic acid, bromopropane sulfonic acid and 3-bromo-2-oxy-propane sulfonic acid).

In place of the lower haloalkanoic acid salts or haloalkane sulfonic acid salts it is also possible to employ inner anhydrides of lower hydroxyalkanoic acids (such as propiolactone or butyrolactone) or of lower hydroxyalkane sulfonic acids (such as 1,3-propanesulfone or 1,4-butanedisulfone). The use of the latter compounds has proved to be especially advantageous with respect to the final yield, because the sultones, particularly the 1,3-sultones, react so rapidly and completely with the ethylene-bis-dithiocarbamates that the alkaline reaction of the still unreacted bis-dithiocarbamates does not have a cleaving effect upon the esters already formed. The ethylene-bis-dithiocarbamyl ester salts thus obtained have the formula:

wherein R represents a radical selected from the group consisting of hydrogen and lower alkyl; Y represents a water-solubilizing group selected from the group consisting of —COOMe and —SO₃Me and Me represents an alkali metal; Z represents a radical selected from the group consisting of hydrogen and hydroxy; n represents an integer from 1 to 4; and m represents an integer from 1 to 2. These alkali metal salts, such as the sodium ethylene-1,2-bis(dithiocarbamyl-S-propane-ω-sulfonate) formed with the aid of 1,3-propane-sulfone, may be further reacted without isolation because the subsequent reactions may also be performed in water. However, they may, if necessary, also be isolated by salting out and drying and may be further reacted after their isolation.

For transformation into the dithiobiuret derivatives according to the invention, the aqueous solution of the start-

ing alkali metal salt is admixed, accompanied by vigorous stirring, with at least one equivalent of ammonia or of a primary or secondary amine which may be of an aliphatic, cycloaliphatic or araliphatic nature.

Suitable monoamines or polyamines of the formula

for the reaction with the ethylene-1,2-bis-dithiocarbamic acid esters are the primary and secondary amines with 1 to 22 carbon atoms, such as alkylamines having from 1 to 22 carbon atoms, for example, ethylamine, butylamine, octylamine, dodecylamine, octadecylamine; dialkylamines having from 2 to 22 carbon atoms, for example, dimethylamine, diethylamine, dioctylamine; alkylamines having from 3 to 22 carbon atoms, for example, oleylamine; phenylalkylamines having from 7 to 22 carbon atoms, for example, benzylamine; hydroxylalkylamines having from 2 to 22 carbon atoms, for example, ethanolamine; cycloalkylamines having from 5 to 6 carbon atoms, for example, cyclohexylamine; alkylcycloalkylamines having from 7 to 22 carbon atoms, for example, methylcyclohexylamine; alkylcycloalkenylamines having from 7 to 22 carbon atoms, for example, naphthylamine; alkylene diamines having from 2 to 22 carbon atoms, for example, ethylenediamine, propylenediamine, butylenediamine; alkylaminoalkylamines having from 3 to 22 carbon atoms, for example, N-ethyl-ethylenediamine; dialkylaminoalkylamines having from 4 to 22 carbon atoms, for example, N,N-diethyl-propylenediamine, N,N-diethyl-ethylene-diamine, N,N-dimethyl-propylenediamine; polyalkylamines having from 4 to 22 carbon atoms, for example, diethylenetriamine; piperidine; pyrrolidine; piperazine, morpholine and glycine.

Accompanied by cleavage of both dithiocarbamyl radicals at the CS—S-bond, two equivalents of mercaptoalkane carboxylic acid salts or mercaptoalkanesulfonic acid salt are formed. The ethylene-bis-isothiocyanic acid, which is thereby formed as an intermediate, combines with the ammonia or amines present, whereby the formation of the dithiobiuret structure occurs, accompanied by ring closure.

The reaction between these starting components takes place smoothly by stirring for several hours, possibly at elevated temperatures of 20 to 100° C., preferably 50 to 60° C. The reaction, however, should be conducted at temperatures of 60° C. or below, if possible. If the amine reactant used in the reaction, such as the high molecular weight amines of the fatty series, is difficultly soluble in water, a solution promoter, such as alcohol, may be added to the mixture without adversely influencing the yield. The substituted thioureas produced in this manner are all so difficultly soluble in water that they separate out of the reaction mixture in crystalline form after a short period of time and may be isolated by filtration.

It has been found that when primary amines are reacted, the alkali metal hydroxide may be substantially, and in many cases even completely, replaced by excess amine without changing the course of the reaction. When secondary amines are used, the concurrent use of the full amount of alkali metal hydroxide is in most cases indispensable and large excesses of amine are best avoided if the reaction is to lead to the product according to the invention and if the formation of tetra-alkylated ethylene-bis-thioureas is to be avoided. Substituted ethylene-bis-thioureas do not form until the dithiobiurets are treated at elevated temperatures for longer periods of time with amines. This is a reaction which generally proceeds more readily with the dithiobiuret produced from secondary amines than with those produced from primary amines,

which is the reason why, when secondary amines are employed, an excess of amine must be avoided, whereas, with primary amines, the alkali metal hydroxide may substantially be replaced by the amine.

To illustrate the course of the reaction, assuming the use of 1,3-propanesultone as the esterification agent and ethylamine as the amine reactant, the reaction proceeds according to the following equation:

The colorless compounds which are obtainable with satisfactory yields by the present process and whose preparation is illustrated by the following examples, are valuable brightening additives for electroplating baths or intermediate products for their preparation. Furthermore, they may be employed as corrosion inhibitors and vulcanization accelerators. The mercaptoalkane carboxylic acids or mercaptoalkane sulfonic acids formed as side products may be used for the same purposes; in addition, they are valuable agents for permanent wave preparations.

The following examples are illustrative of my invention. They are not to be considered as limitative, however, as other expedients known to those skilled in the art can be employed.

EXAMPLE I

1-butylthiocarbamyl-2-imidazolidinethione

45 Sodium ethylene-1,2-bis-(dithiocarbamyl-S-propane- ω -sulfonate) was prepared by slowly adding 12 parts by weight of ethylene diamine (0.2 mol) and then 80 parts by weight of a 20% sodium hydroxide solution (0.4 mol) to a vigorously stirred suspension of 30.4 parts by weight of carbon disulfide (0.4 mol) in 150 parts by volume of water. The solution was stirred until it became clear, then 49 parts by weight of 1,3-propanesultone (0.4 mol) were added thereto and the reaction mixture was stirred. The sodium ethylene-1,2-bis-(dithiocarbamyl-S-propane- ω -sulfonate) was obtained by salting out.

60 100 parts by weight of sodium ethylene-1,2-bis(dithiocarbamyl-S-propane- ω -sulfonate) (0.2 mol) were dissolved in 300 parts by volume of water and the resulting solution, after adding 15 parts by weight of butylamine (0.2 mol), was admixed dropwise with 80 parts by weight of a 20% sodium hydroxide solution (0.4 mol). The 1-butylthiocarbamyl-2-imidazolidinethione formed thereby 65 separated out after a short period of time in crystalline form. After stirring the mixture for several hours, toward the end while cooling it on ice, the precipitate was separated by vacuum filtration and the product, which was formed in ample quantity, was recrystallized from 70 seven times its amount of isopropanol. The melting point of the analytically pure substance was 135–137° C.

75 The same compound was obtained when, in place of the 20% sodium hydroxide, an equivalent amount of butylamine, that is, a total of 43.8 parts by weight of this amine (0.6 mol), was added to the solution of sodium

ethylene - 1,2 - bis(dithiocarbamyl-S-propane- ω -sulfonate) prepared according to the method described in the preceding example. After six hours of reaction at room temperature the yield was 53% of theory.

EXAMPLE II

*1-n-octylthiocarbamyl-2-imidazolidinethione*By working in close analogy to the method described in the previous example, but using 26 parts by weight of n-octylamine (0.2 mol) in place of butylamine, 1-n-octylthiocarbamyl-2-imidazolidinethione was obtained with a yield of 65%, which was recovered analytically pure by recrystallization from isopropanol. The melting point was 101-101.5° C.

EXAMPLE III

*1-dodecylthiocarbamyl-2-imidazolidinethione*125 parts by volume of alcohol, 37 parts by weight of dodecylamine (0.2 mol) and 80 parts by volume of 20% sodium hydroxide (0.4 mol) were added to a solution of 100 parts by weight of sodium ethylene-1,2-bis(dithiocarbamyl-S-propane- ω -sulfonate) (0.2 mol) in 300 parts by volume of water. The 1-dodecylthiocarbamyl-2-imidazolidinethione which separated out with excellent yield in the course of several hours stirring at room temperature was obtained in the form of fine needles by recrystallization from twenty times its amount of acetone, methanol or isopropanol; the analytically pure needles melted at 105-107° C.

For the preparation of a vulcanizable rubber composition for automobile tires, the following ingredients were admixed by kneading:

	Parts by weight
Smoked sheets	100
Zinc oxide	3
Carbon black	45
Spruce rosin	2.5
Stearic acid	3
Paraffin	0.75
Phenylnaphthalene	1.5
1-dodecylthiocarbamyl-2-imidazolidinethione (accelerator)	0.6
Sulfur	3.0

After shaping, this mixture was vulcanized for twenty-five minutes at 145° C. in the usual manner.

EXAMPLE IV

*1-dimethylthiocarbamyl-2-imidazolidinethione*12 parts by weight of ethylene diamine (0.2 mol) and then 80 parts by weight of a 20% sodium hydroxide solution (0.4 mol) were slowly added to a vigorously stirred suspension of 30.4 parts by weight of carbon disulfide (0.4 mol) in 150 parts by volume of water. The

solution became clear after two hours of stirring, and then 49 parts by weight of 1,3-propanesultone (0.4 mol) were added thereto and the mixture was stirred until the reaction mixture had become virtually neutral. After 5 addition of 32.5 parts by weight of a 33% aqueous dimethylamine solution (0.25 mol) and an additional 80 parts by weight of 20% sodium hydroxide (0.4 mol) the reaction mixture began to turn cloudy and the 1-dimethylthiocarbamyl-2-imidazolidinethione began to separate out in crystalline form. After stirring the reaction mixture for several additional hours, toward the end at the temperature of ice, the precipitate was separated by vacuum filtration and was washed with water. 22 parts by weight of the product were obtained, which corresponds to a yield of 58% of theory. Recrystallized from 40 times its amount of ethyl alcohol, the compound was obtained analytically pure and had a melting point of 184 to 186° C.

EXAMPLE V

*1-diethylthiocarbamyl-2-imidazolidinethione*By working in close analogy to the method described in Example IV, but using 15 parts by weight of diethylamine (0.2 mol) in place of the dimethylamine solution and working up the reaction mixture in the same manner, 18 parts by weight of 1-diethylthiocarbamyl-2-imidazolidinethione were obtained, which corresponds to a yield of 41% of theory. The analytically pure compound recrystallized from isopropanol at a melting point of 123-125° C.

EXAMPLE VI

*1-thiocarbamyl-2-imidazolidinethione*By working in close analogy to the method described in Example I, that is, by adding 80 parts by weight of 20% sodium hydroxide (0.4 mol) and 70 parts by weight of 25% ammonia while stirring to a solution prepared by 100 parts by weight of sodium ethylene-1,2-bis(dithiocarbamyl-S-propane- ω -sulfonate) (0.2 mol) and 250 parts by weight of water, the 1-thiocarbamyl-2-imidazolidinethione formed thereby crystallized out soon thereafter. The reaction mixture was allowed to stand overnight, the precipitate was separated by vacuum filtration and was then recrystallized from 100 times its amount of water. The analytically pure compound, which was obtained with a yield of about 20%, melted at 192-194° C.

EXAMPLE VII

*1-pentamethylenethiocarbamyl-2-imidazolidinethione*17 parts by weight of piperidine (0.2 mol) and 80 parts by weight of 20% sodium hydroxide (0.4 mol)

were added to a solution of sodium ethylene-1,2-bis-(dithiocarbamyl-S-propane- ω -sulfonate) prepared as described in Example IV. 1-pentamethylenethiocarbamyl-2-imidazolidinethione which formed with a yield of 60% was recrystallized from 80 times its amount of isopropanol or from a mixture of dimethylformamide and water, and had a melting point of 178-179° C.

The same compound was obtained when, in place of 1,3-propanesultone, 46.6 parts by weight of sodium monochloroacetate (0.4 mol) were added to a solution of sodium ethylene-1,2-bis-dithiocarbamic acid prepared as described in Example IV, and after stirring this mixture for 4 hours, 17 parts by weight of piperidine (0.2 mol) and 80 parts by weight of 20% sodium hydroxide (0.4 mol) were added thereto. The crystalline product which separated out after several hours' stirring with somewhat smaller yield was identical with the product obtained above.

EXAMPLE VIII

*I-(3'-oxapentamethylene)-thiocarbamyl-2-imidazolidinethione*By following the procedure described in Example IV, but using in place of dimethylamine 17.5 parts by weight of morpholine (0.2 mol), 1-(3'-oxapentamethylene)-thiocarbamyl-2-imidazolidinethione was obtained which, recrystallized from a mixture of equal parts of dimethylformamide in water, had a melting point of 191-192° C.

EXAMPLE IX

*I-benzylthiocarbamyl-2-imidazolidinethione*Following a procedure analogous to that described in Example IV, but using 21.5 parts by weight of benzylamine (0.2 mol) in place of dimethylamine, 1-benzylthiocarbamyl-2-imidazolidinethione was obtained with a yield of 68% of theory. After recrystallization from 15 times its amount of isopropanol, the product was obtained analytically pure and had a melting point of 132-133° C.

EXAMPLE X

*I-cyclohexylthiocarbamyl-2-imidazolidinethione*By following a procedure analogous to that described in Example I, but using 19.6 parts by weight of cyclohexylamine (0.2 mol) in place of butylamine, 1-cyclohexylthiocarbamyl-2-imidazolidinethione was obtained with a yield of 55% of theory. Recrystallized from 7 times its amount of methanol, it has a melting point of 150-152° C.

EXAMPLE XI

*I,I'-(ethylene-di-thiocarbamyl)-bis-2-imidazolidinethione*5

10

15

30

35

60

65

70

75

EXAMPLE XII

By following the procedure described in Example IV, 20 but using 6.6 parts by weight of ethylenediamine (0.11 mol) in place of dimethylamine, 14 parts by weight of the bis-dithiobiuret having the above formula were obtained with a yield of 20% of theory. When precipitated from 15 times its amount of a mixture of 2 parts 25 of dimethylformamide and 1 part of water the product had a melting point of 213-215° C.

EXAMPLE XIII

*I-carboxymethylthiocarbamyl-2-imidazolidinethione*30

35

120 parts by weight of a 20% sodium hydroxide solution (0.6 mol) and 27.9 parts by weight of ethyl glycine hydrochloride (0.2 mol) were added, while stirring, to an aqueous solution of 100 parts by weight of sodium ethylene-1,2-bis-(dithiocarbamyl-S-propane- ω -sulfonate) (0.2 mol) which was prepared in a manner analogous to 45 that described in Example IV, and the resultant reaction mixture was stirred for 2 hours at room temperature and then for an additional hour at 45° C. The slightly turbid mixture was filtered and the filtrate was then made just acid to congo red by adding diluted hydrochloric acid. 50 An ample amount of crystalline 1-carboxymethylthiocarbamyl-2-imidazolidinethione separated out and the mixture was allowed to stand for several hours on ice. Thereafter it was vacuum filtered, the filter cake was dried and recrystallized from alcohol or methanol. The analytical 55ly pure product was obtained in the form of long needles having a melting point of 186-188° C.

EXAMPLE XIII

*I-(3'-diethylamino-propylthiocarbamyl)-2-imidazolidinethione*60

65

70

75

80 parts by weight of a 20% solution of sodium hydroxide (0.4 mol) and 26 parts by weight of N,N-diethyl-1,3-propylenediamine (0.2 mol) were added to a solution 75 of sodium ethylene-1,2-bis-(dithiocarbamyl-S-propane- ω -

sulfonate) (0.2 mol) prepared analogous to the method described in Example IV. The 1-(3'-diethylamino-propylthiocarbamyl) - 2 - imidazolidinethione which crystallized out after a short period of time was separated by vacuum filtration after stirring the mixture for 3 hours and was then recrystallized from 15 times its amount of ethanol. 25 parts by weight of the product, corresponding to a yield of 45% of theory, were obtained. The analytically pure base which is readily soluble in dilute acids had a melting point of 151-153° C.

8 to 12 mgs. of the above compound were added to a nickel electroplating bath which contained 265 gms. per liter of crystalline nickel sulfate, 53 gms. per liter of crystalline nickel chloride, and 33 gms. per liter of boric acid, and in addition contained 2.5 gms. of sodium di-*o*-tolyl-disulfamide and 0.2 gm. of sodium dodecylsulfate (as wetting agent). When this electroplating bath was operated at temperature of 55° C. a full bright electroplate was obtained within a current density range of 0.5 to 8 amperes per decimeter² with an excellent leveling effect.

For the preparation of a vulcanizable rubber composition for automobile tires, the following ingredients were admixed by kneading:

	Parts by weight
Smoked sheets	100
Zinc oxide	3
Carbon black	45
Spruce rosin	2.5
Stearic acid	3
Paraffin	0.75
Phenylnaphthalene	1.5
1-(3'-diethylamino - propylthiocarbamyl) - 2 - imidazolidinethione (as accelerator)	0.6
Sulfur	3.0

After shaping, this mixture was vulcanized for 25 minutes at 145° C. in the usual manner.

EXAMPLE XIV

1-dimethylthiocarbamyl-4(or 5)-methyl-2-imidazolidinethione

and

By using a procedure closely analogous to that described in Example IV, but using 14.8 parts by weight 1,2-propylenediamine in place of 1,2-ethylenediamine, well crystallized 1-dimethylthiocarbamyl - methyl-2-imidazolidinethione was obtained with a 44% yield under the conditions described for the reaction with dimethylamine in Example IV. However, the question remains open as to whether the methyl group is in the 4-position or in the 5-position of the imidazoline ring or whether a mixture of isomers is obtained. The compound crystallized from 10 times its amount of alcohol in the form of coarse, colorless crystals which have a melting point of 163-164° C.

EXAMPLE XV

1-(3'-diethylamino-propylthiocarbamyl)-4(or 5)-methyl-2-imidazolidinethione

and

26 parts by weight of N,N-diethyl-1,3-propylenediamine (0.2 mol) and 80 parts by weight of 20% sodium hydroxide were added to a solution of sodium propylene-1,2-bis-(dithiocarbamyl-S-propane- ω -sulfonate) prepared in a manner analogous to that described in Example IV, but using 14.8 parts by weight of 1,2-propylenediamine (0.2 mol) in place of 1,2-ethylenediamine. The 1-(3'-diethylamino - propylthiocarbamyl) - methyl-2-imidazolidinethione which soon separated out in crystalline form with a yield of about 43% of theory was separated by vacuum filtration after 4 hours of stirring, washed with water, dried and recrystallized from 6 times its amount of isopropanol or a mixture of equal parts of gasoline and benzene. The question as to whether the methyl group is in the 4-position or in the 5-position of the imidazoline ring or whether a mixture of isomers is obtained remains open. The compound had a melting point of 104-105° C.

EXAMPLE XVI

1-(3'-dimethylamino-propylthiocarbamyl)-2-imidazolidinethione

By using a procedure analogous to that described in Example XIII, but using 20.4 parts by weight of N,N-dimethyl-1,3-propylenediamine (0.2 mol) in place of N,N-diethyl-1,3-propylenediamine, 1-(3'-dimethylamino-propylthiocarbamyl) - 2-imidazolidinethione was obtained with a yield of about 43% of theory. Recrystallized from 15 times its amount of isopropanol, it had a melting point of 161-163° C.

EXAMPLE XVII

1-(2'-diethylamino-ethylthiocarbamyl)-2-imidazolidinethione

When the N,N-diethyl-1,3-propylenediamine used in Example XIII was replaced by 23.2 parts by weight of N,N-diethyl-1,2-ethylene diamine (0.2 mol), and the same procedure was used, 1-(2'-diethylaminoethylthiocarbamyl)-2-imidazolidinethione was obtained which, recrystallized from 10 times its amount of isopropanol, had a melting point of 131-133°C.

EXAMPLE XVIII

1-[3'-(morpholine-N)-propylthiocarbamyl]-2-imidazolidinethione

Using a procedure analogous to that described in the two preceding examples, but using 29 parts by weight of N-morpholine-1,3-propylenediamine (0.2 mol) as the basic reactant, 1-[3'-(morpholine-N)-propylthiocarbamyl]-2-imidazolidinethione was obtained with a satisfactory yield. It had a melting point of 142.5-143.5°C. By recrystallization from 10 times the amount of isopropanol it was obtained in its pure form.

The above examples disclose many of the embodiments of my invention. It is to be understood that other embodiments, such as utilization of other reactants, alkali metal hydroxides, etc., known to those skilled in the art, may be employed without departing from the spirit of the invention or the scope of the appended claims.

I claim:

1. The process of producing 1-thiocarbamyl-2-imidazolidinethione of the formula:

wherein R is a radical selected from the group consisting of hydrogen and lower alkyl; and R₁ and R₂ are radicals selected from the group consisting of hydrogen, alkyl of from 1 to 22 carbon atoms, alkenyl of from 3 to 22 carbon atoms, hydroxyalkyl of from 2 to 22 carbon atoms, carboxyalkyl of from 2 to 8 carbon atoms, cycloalkyl of from 5 to 6 carbon atoms, alkylcycloalkyl of from 7 to 22 carbon atoms, alkylcycloalkenyl of from 7 to 22 carbon atoms, aminoalkyl of from 2 to 22 carbon atoms, phenylalkyl of from 7 to 22 carbon atoms, alkylaminoalkyl of from 3 to 22 carbon atoms, dialkylaminoalkyl of from 4 to 22 carbon atoms, aminoalkylaminoalkyl of from 4 to 22 carbon atoms, and, when taken together with the nitrogen atom, piperidino, pyrrolidino, piperazino and morpholino, which comprises the steps of reacting a water-soluble ester compound of the formula:

wherein R is a radical selected from the group consisting of hydrogen and lower alkyl; Y is a water-solubilizing group selected from the group consisting of -COOMe and -SO₃Me and Me is an alkali metal; Z is a radical selected from the group consisting of hydrogen and hydroxy; n represents an integer from 1 to 4; and m represents an integer from 1 to 2, dissolved in an aqueous

solution with the stoichiometric amount of a compound having the formula

where R₁ and R₂ have the above meanings, in the presence of an alkaline reactant selected from the group consisting of alkali metal hydroxides and

where R₁ and R₂ have the above meanings, at a temperature between about 20°C. and about 100°C. and recovering said 1-thiocarbamyl-2-imidazolidinethione.

2. The process of producing 1-thiocarbamyl-2-imidazolidinethione which comprises the steps of reacting sodium ethylene-1,2-bis-(dithiocarbamyl-S-propane-ω-sulfonate), dissolved in an aqueous solution with the stoichiometric amount of ammonia in the presence of sodium hydroxide at a temperature between about 20°C. and 60°C. and recovering said 1-thiocarbamyl-2-imidazolidinethione.

3. The process of producing 1-butylthiocarbamyl-2-imidazolidinethione which comprises the steps of reacting sodium ethylene-1,2-bis-(dithiocarbamyl-S-propane-ω-sulfonate), dissolved in an aqueous solution with the stoichiometric amount of butylamine in the presence of sodium hydroxide at a temperature between about 20°C. and 60°C. and recovering said 1-butylthiocarbamyl-2-imidazolidinethione.

4. The process of producing 1-butylthiocarbamyl-2-imidazolidinethione which comprises the steps of reacting sodium ethylene-1,2-bis-(dithiocarbamyl-S-propane-ω-sulfonate), dissolved in an aqueous solution with the stoichiometric amount of butylamine in the presence of an excess of butylamine at a temperature between about 20°C. and 60°C. and recovering said 1-butylthiocarbamyl-2-imidazolidinethione.

5. The process of producing 1-thiocarbamyl-2-imidazolidinethione of the formula:

wherein R is a radical selected from the group consisting of hydrogen and lower alkyl; and R₁ and R₂ are radicals selected from the group consisting of hydrogen, alkyl of from 1 to 22 carbon atoms, alkenyl of from 3 to 22 carbon atoms, hydroxyalkyl of from 2 to 22 carbon atoms, carboxyalkyl of from 2 to 8 carbon atoms, cycloalkyl of from 5 to 6 carbon atoms, alkylcycloalkyl of from 7 to 22 carbon atoms, alkylcycloalkenyl of from 7 to 22 carbon atoms, aminoalkyl of from 2 to 22 carbon atoms, phenylalkyl of from 7 to 22 carbon atoms, alkylaminoalkyl of from 3 to 22 carbon atoms, dialkylaminoalkyl of from 4 to 22 carbon atoms, aminoalkylaminoalkyl of from 4 to 22 carbon atoms, and, when taken together with the nitrogen atom, piperidino, pyrrolidino, piperazino and morpholino, which comprises the steps of reacting alkali metal salts of a dithiocarbamic acid of the formula:

where R has the above assigned meaning with a water-solubilizing esterifying component selected from the group consisting of alkali metal lower haloalkanoates, alkali metal lower haloalkane sulfonates, lower hydroxyalkanoic acid lactones and lower hydroxyalkane sulfonic acid sul-

15

tones, dissolving the water-soluble ester compound formed thereby of the formula:

wherein R is a radical selected from the group consisting of hydrogen and lower alkyl; Y is a water-solubilizing group selected from the group consisting of —COOMe and —SO₃Me and Me is an alkali metal; Z is a radical selected from the group consisting of hydrogen and hydroxy; n is an integer from 1 to 4; and m is an integer from 1 to 2, dissolved in an aqueous solution with the stoichiometric amount of a compound having the formula

where R₁ and R₂ have the above meanings, in the presence of an alkaline reactant selected from the group consisting of alkali metal hydroxides and

where R₁ and R₂ have the above meanings, at a temperature between about 20° C. and about 100° C. and recovering said 1-thiocarbamyl-2-imidazolidinethione.

16

6. 1-thiocarbamyl-2-imidazolidinethione.
7. 1-butylthiocarbamyl-2-imidazolidinethione.
8. 1-octylthiocarbamyl-2-imidazolidinethione.
9. 1-dimethylthiocarbamyl-2-imidazolidinethione.
10. 1-(3'-oxapentamethylene)-thiocarbamyl-2-imidazolidinethione.
